UNITED STATES PATENT OFFICE.

CHARLES E. MANLEY, OF MARICOPA, CALIFORNIA.

WASHBOARD.

1,293,613.

Specification of Letters Patent.

Patented Feb. 4, 1919.

Application filed October 31, 1917. Serial No. 199,516.

To all whom it may concern:

Be it known that I, CHARLES E. MANLEY, a citizen of the United States, residing at Maricopa, in the county of Kern and State of California, have invented certain new and useful Improvements in Washboards, of which the following is a specification, reference being had to the accompanying drawings.

10 This invention relates to certain improvements in wash boards and it is an object of the invention to provide a device of this general character including a novel and improved soap box which is so constructed as 15 to permit the soap to be readily and conveniently taken therefrom especially when the soap is wet.

It is also an object of the invention to provide a device of this general character having 20 a novel and improved soap box which is provided with means wherein a drainage is afforded which is not liable to become clogged or obstructed and which also assures a ventilation to facilitate the drying of the soap.

25 The invention consists in the details of construction and in the combination and arrangement of the several parts of my improved wash board whereby certain important advantages are attained and the device 30 is rendered simpler, less expensive and otherwise more convenient and advantageous for use, all as will be hereinafter more fully set forth.

The novel features of the invention will 35 hereinafter be definitely claimed.

In order that my invention may be the better understood, I will now proceed to describe the same with reference to the accompanying drawings, wherein—

40 Figure 1 is a fragmentary elevational view of the upper portion of a wash board constructed in accordance with an embodiment of my invention;

Fig. 2 is a sectional view taken substantially on the line 2—2 of Fig. 1; looking in the direction of the arrow;

Fig. 3 is a longitudinal sectional view taken through the device as illustrated in Fig. 1;

50 Fig. 4 is a fragmentary elevational view illustrating a soap box constructed in accordance with an embodiment of my invention and in applied position.

Fig. 5 is a sectional view taken substantially on the line 5—5 of Fig. 4;

55

Fig. 6 is a sectional view taken substantially on the line 6—6 of Fig. 5; and

Fig. 7 is a fragmentary view in rear elevation illustrating the spring member co-acting with the back of a wash board for maintaining the holder in applied position.

As disclosed in Figs. 1 to 3 of the accompanying drawings 1—1 denote the side rails of my improved wash board connected at their upper ends by the top plate 2. Said side 65 rails 1 are also connected at a predetermined point inwardly of the top plate or back 2 by the soap bar 3 which affords the inner or lower wall for the soap box S.

R denotes a rubbing board of any ordinary 70 or preferred construction.

The opposed faces of the side rails 1 are provided with the longitudinally disposed slots 4 occupying a plane substantially flush with the rear face of the soap bar 3 and extending from the outer ends of the side rails 1 to a point substantially flush with the outer longitudinal margin of the soap bar 3. The slots 4 have seated therein the marginal flanges 5 of the plate B which constitutes 80 the bottom of the soap box S.

The plate B is provided with the corrugations 6 extending longitudinally of the wash board and preferably of a depth of substantially three-fourths of an inch. The 85 lower marginal portion of the plate B underlies the soap bar 3 and is secured to said bar intermediate its corrugations 6 by the fastening members 7 which may be nails, screws, or the like. The upper marginal portion of the 90 plate B is seated within a groove 8 produced in the inner face of the top plate or back 2, said groove 8 conforming to the corrugated portion of the plate B.

The particular manner whereby the plate 95 B is mounted results in materially large openings a rearwardly of the soap bar 3 which assures requisite drainage of the soap box S and also permits such ventilation as to expedite the drying of the soap within 100 the box. It is also to be noted that the location of the plate B results in the openings a being located rearwardly of the rubbing board R, whereby the life of the bar 3 is materially prolonged.

105

In practice the side rails 1, the top plate

or back 2, and the soap bar 3 are preferably made of wood, while the plate B is of metal.

By having the corrugations 6 of the plate B of a material depth as hereinbefore specified, it is possible to insert a digit of the hand beneath the soap within the box S so that said soap may be readily and conveniently removed. This is especially desirable when the soap is wet and when the hand of the person may also be wet. It is a well known fact that under ordinary conditions it is an extremely difficult matter to remove the soap from a box of the washboard but with the present invention the removal of the soap may be readily accomplished irrespective of the size of the soap cake or its condition. It is also to be noted that by having the lower marginal portion of the plate B secured to the under surface of the soap bar 3, the possibility of a cake of soap after becoming worn thin slipping into the tub or other container is prevented.

It is also to be observed that the side rails 1 are of such a width as to have their rear edges positioned outwardly of the corrugations 6 of the plate B so that when the wash board is in applied position the possibility of contact with the plate B is substantially entirely eliminated and which would otherwise have a tendency to injure said plate.

As illustrated in Figs. 4 to 7 I disclose a removable soap tray adapted to be positioned within the soap box S' of the washboard. As herein embodied my improved tray is formed of sheet metal having one side marginal portion doubled upon itself to form an upstanding side flange 9 while the opposite marginal portion is provided 40 with an upstanding flange 10 adapted to contact with the inner face of one of the side rails 1^a of the washboard. The flange 10 is provided with an outwardly directed flange 11 returned upon itself as at 12 and which returned portion 12 contacts directly with the outer face of the side rail 1^a. The flange 11 and the returned portion 12 thereof extend beyond the outer faces of the side rail 1^a whereby a barrel or sleeve is afforded 50 and through the opposite ends of which are disposed the end portions 14 of the wire strand and the extremities of said end portions 14 are inwardly and laterally directed as at 15 whereby the end portions 14 are held against rotation. The portions of the wire strand immediately adjacent the portions 14 are extended laterally as at 16 to contact with the outer side faces of the rail 1^a and the portions 16 are continued by the 60 inwardly directed extensions 17 adapted to underlie the side rail 1^a. The portions 17 are connected by the intermediate straight portion 18.

The portion of the tray intermediate the flanges 9 and 10 is corrugated as indicated at

19 and the corrugations adjacent the top plate 2^a of the wash board are of greater depth than the portions of the corrugations adjacent the soap bar 3^a. It is also to be particularly noted that the forward end 70 portions of the tray partially underlies the soap bar 3^a which assures a drainage of the tray and also permits ventilation to expedite the drying of the soap within the tray. In practice it has been found of advantage 75 to have the portions of the corrugations immediately adjacent the top plate or back 2^a about three-quarters of an inch deep and gradually reducing toward the opposite end to a depth of about one-quarter inch. The 80 corrugations readily permit the thumb or other digit of a hand to be engaged beneath a cake of soap within the tray so that the soap may be readily and conveniently removed especially when the soap is wet or 85 the hand of the person also be wet. While the wire strand which underlies the side rail 1^a serves to maintain the tray in applied position it will also be self evident 90 that said tray is further maintained in position by the forward end portion thereof which extends beneath the soap bar 3^a as is particularly illustrated in Figs. 4 and 5.

From the foregoing description, it is thought to be obvious that a wash board constructed in accordance with my invention is of an extremely simple and comparatively inexpensive nature and is particularly well adapted for use by reason of the convenience and facility with which it may be assembled, and it will also be obvious that my invention is susceptible of some change and modification without material departure from the principles and spirit thereof and for this reason I do not wish to be understood as limiting myself to the precise arrangement and formation of the several parts herein shown in carrying out my invention in practice except as hereinafter claimed.

I claim:

1. A soap tray adapted to be positioned within the soap box of a wash board and provided with means for maintaining the same in applied position, the bottom of said tray being corrugated, said corrugations decreasing in depth from one end toward the other, said corrugations being of a depth to permit the insertion of a digit of a hand beneath an article resting upon the bottom 115 of the tray and extending across the corrugations.

2. In combination with a wash board including a soap box, a tray insertible within said soap box and provided with side flanges, one of said flanges being arranged for contact with a wall of the box, means carried by said flange and overlying the rear face of the soap box for maintaining the tray in applied position, the bottom of said tray 120

being corrugated, said corrugations being of a depth to permit the insertion of a digit of a hand beneath an article resting upon the bottom of the tray and extending across the corrugations.

3. In combination with a wash board including a soap box, a tray fitting within said box and provided with upstanding side flanges, one of said flanges contacting with a side rail of the box, said flange being provided with a second flange overlying the outer face of the side rail, and a spring member carried by said second flange and overlying the rear of the soap box for maintaining said tray within the box.

4. In combination with a wash board including a soap box, a tray insertible within said soap box, the bottom of said tray be-

ing corrugated, the forward marginal portion of the bottom of said tray underlying 20 the soap bar of the box.

5. In combination with a wash board including a soap box, a tray insertible within said soap box and provided with a side flange, said flange being provided with a second 25 flange overlying the outer face of the side rail, and means carried by the second flange and overlying the rear of the soap box for maintaining said tray within the box.

In testimony whereof I hereunto affix my 30 signature in the presence of two witnesses.

CHARLES E. MANLEY.

Witnesses:

M. Y. WHITE,
T. L. BIGELOW.
